[57] CLAIM

I claim the ornamental design for a scooter frame, as shown and described.

DESCRIPTION

FIG. 1 is an upper frontal perspective view of a scooter frame showing my design.

FIG. 2 is an end view thereof;

FIG. 3 is a front view thereof;

FIG. 4 is a side view thereof;

FIG. 5 is an opposite side view thereof;

FIG. 6 is a plan view thereof;

FIG. 7 is a bottom view thereof; and,

FIG. 8 is an environmental perspective view with the broken line showing of wheel-like elements and a board-like element for illustrative purposes only and forming no part of the claimed design.
